(57) **CLAIM**

The ornamental design for a refrigerator, as shown and
described.

DESCRIPTION

FIG. 1 is a perspective view of a refrigerator showing my new
design;

FIG. 2 is a front elevational view thereof;

FIG. 3 is a rear elevational view thereof;

FIG. 4 is a left side view thereof;

FIG. 5 is right side view thereof;

FIG. 6 is a top plane view thereof;

FIG. 7 is a bottom view thereof; and,

FIG. 8 is a reference view similar to FIG. 1, showing a state in
which a right-top door of the refrigerator is completely
opened.

The broken lines shown in the drawings illustrate portions of
the refrigerator that form no part of the claimed design. The
subject design is a partial design and the solid line shows a
boundary of the portion to be claimed. The main point of the
subject design is the combination of the figure and the shape
of "refrigerator".
